(57) **CLAIM**

The ornamental design for a bearing greaser grease tool, as shown and described.

DESCRIPTION

FIG. 1 is a front perspective view of a bearing greaser grease tool, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the bearing greaser grease tool in a use state 1 thereof;

FIG. 10 is a perspective view showing the bearing greaser grease tool in a use state 2 thereof; and,

FIG. 11 is an enlarged detail view of area 11 in FIG. 1.

The broken lines in the drawings illustrate the portions of the bearing greaser grease tool, which form no part of the claimed design.

The dash-dot-dash broken lines encircling the enlarged views are for annotative purposes only and form no part of the claim thereof.
